Primary Examiner — Cynthia Ramirez(74) *Attorney, Agent, or Firm* — Kearney McWilliams Davis; Erik J. Osterrieder(57) **CLAIM**

The ornamental design for a pallet, as shown and described.

DESCRIPTION

FIG. 1 is a front view of a pallet showing my new design; FIG. 2 is a perspective view from front and side;

FIG. 3 is a left-side view;

FIG. 4 is right-side view;

FIG. 5 is a perspective view from back and side;

FIG. 6 is a top view;

FIG. 7 is a front view of multiple, stacked pallets;

FIG. 8 is a bottom view; and,

FIG. 9 is a back view.

The broken lines in the figures show portions of the pallet that are not part of the claimed design.

The additional broken lines in FIG. 7 show environment and form no part of the claimed design.
